UNITED STATES PATENT OFFICE.

CHARLES F. HOFFMAN, OF LANSING, MICHIGAN.

RACK.

No. 856,584.

Specification of Letters Patent.

Patented June 11, 1907.

Application filed October 23, 1906. Serial No. 340,141.

To all whom it may concern:

Be it known that I, CHARLES F. HOFFMAN, a citizen of the United States, residing at Lansing, in the county of Ingham and State 5 of Michigan, have invented certain new and useful Improvements in Racks, of which the following is a specification, reference being had to the accompanying drawing.

My invention relates to improvements in devices for the support and display of sundry articles, and the object of my invention is to provide a rack or stand which will be cheap in manufacture, simple in construction and easily packed for shipment, and for storage 15 when not in use.

In the drawings illustrating the principle of my invention and the best mode now known to me of applying that principle, Figure 1 is a perspective view of my new support; Fig. 2 is a side view thereof; and Fig. 3 is a side view showing the support folded for shipment or storage.

The back *a* of the support is formed with two openings, the opening *b* being at the top 25 and the opening *c* being at the bottom. The opening *b* is so formed as to receive the block *d* attached to the back of a pad of paper *e* upon the sheets of which may be printed any desired advertising matter or other information. The block *d* fits snugly in the opening *b* into which it is pressed from the front, and as the opening narrows from bottom to top, the block is held snugly therein. The lower edge of the paper pad *e* rests upon the shelf *f*.

35 At the bottom of the back *a* there is pivotally mounted in the opening *c* the base *g*; and the opening *c* is of the same shape and size as the base *g*, so that when the base *g* is thrown upwardly against the back *a*, it fits snugly in the opening *c*, as will be obvious from Figs. 1 and 40 3. A prop *h* is hinged to the back *a* at the point *i* and when the support is not in use, the prop may be folded down against the back *a*. The base *g* is provided with studs *j* 45 to hold the more securely any article seated thereon, as the shaving mug *k*.

My new rack may be put to a variety of uses. Instead of the mug *k*, the base *g* may be used to support an inkstand or like article.

The paper of the pad *e* may be used as shaving paper and when suitably printed may serve as a calendar. I desire to be understood as claiming the structure shown, whatever the use to which it may be put.

I claim:

1. In a support of the character described, the combination of a back formed with an opening; and a base, said base being pivotally mounted in the walls of said opening and thereby adapted to fold up into said opening. 50 60

2. In a support of the character described, the combination of a back formed with an opening; and a pad provided with a block, said block fitting snugly into said opening to secure said pad in place upon said back. 65

3. In a support of the character described, the combination of a back formed with an opening which narrows from bottom to top; and a pad provided with a block; said block being pressed into said opening from the front and fitting snugly therein to secure said pad in place upon said back. 70

4. In a support of the character described, the combination of a back provided with an opening; a pad provided with a block which interlocks with the walls of said opening; and a shelf secured to said back for the support of the lower edge of said pad. 75

5. In a support of the character described, the combination of a back formed with an opening; a prop hinged to said back; and a base pivotally mounted in the walls of said opening and thereby adapted to fold up into said opening. 80

6. The combination in a support of the class described of a back; a base for the support of a mug or like article; and a pad; said pad and back being formed with co-operating locking elements, whereby said pad is secured in place upon said back. 85 90

In testimony whereof I have hereunto set my hand this ninth day of October, A. D. 1906, at said Lansing in the presence of two witnesses.

CHARLES F. HOFFMAN.

Witnesses:

FAY REED,
JOSEPH H. DUNNEBACKE.
